UNITED STATES PATENT OFFICE.

CARL WICHT AND WILLIAM E. DIPPERT, OF DES MOINES, IOWA.

DESIGN FOR A HINGE-PLATE FOR TOP-COLLAR FASTENERS.

SPECIFICATION forming part of Design No. 32,280, dated February 27, 1900.

Application filed January 16, 1900. Serial No. 1,691. Term of patent 14 years.

To all whom it may concern:

Be it known that we, CARL WICHT and WILLIAM E. DIPPERT, citizens of the United States of America, and residents of Des Moines, Polk county, Iowa, have invented a new and useful Design for a Hinge-Plate for a Top-Collar Fastener, of which the following is a specification.

The object of this invention is to provide a design for a new, useful, and ornamental hinge-plate for a top-collar fastener; and our invention consists of the design hereinafter set forth, pointed out in our claim, and illustrated by the accompanying drawings, in which—

Figure 1 is a plan of a hinge-plate embodying our design. Fig. 2 is a bottom view of the hinge-plate shown in Fig. 1. Fig. 3 is an edge view or elevation of the hinge-plate. Fig. 4 is a longitudinal section of the hinge-plate on the indicated line 4 4 of Fig. 1.

In the design as shown the numeral 10 designates a plate longitudinally curved and relatively thin as compared with its other dimensions and tapering as to thickness from end to end. An eye or hole 11 of angular

shape is formed in the thicker end portion of the plate 10, laterally of the plate and intermediate of the side margins thereof. The bar 12, forming the closure of the eye or hole 11 and also forming the central portion of the thicker end of the plate 10, is rounded or approximately circular in cross-section. An ear 13 extends laterally from one side margin of the convex face of the plate 10, and the outer end of said ear is rounded.

The characteristic features of the design are to be found in the plate longitudinally curved and formed with an eye in one end portion thereof closed by a rounded bar and an ear extending laterally from the convex face of said bar at one of the side margins thereof.

We claim as our invention—

The design for a hinge-plate of a top-collar fastener, substantially as herein shown and described.

CARL WICHT.

WILLIAM E. DIPPERT.
